(57) **CLAIM**

The ornamental design for a vehicle door protector, as shown and described.

DESCRIPTION

FIG. 1 is a front view of a vehicle door protector showing my new design;

FIG. 2 is a rear view of the vehicle door protector;

FIG. 3 is a right side view of the vehicle door protector;

FIG. 4 is a left side view of the vehicle door protector;

FIG. 5 is a top view of the vehicle door protector;

FIG. 6 is a bottom view of the vehicle door protector; and,

FIG. 7 is a top front side perspective view of the vehicle door protector.

The dash-dash broken lines in the drawings illustrate stitching of the vehicle door protector that form no part of the claimed design. The dash-dot-dash broken lines in the drawings define a boundary of a logo forming no part of the claimed design.
